DESIGN FOR A VELOCIPEDe DECK PLATE

Walter V. Smith, Hammond, Ind., assignor to
Junior Toy Corporation, Hammond, Ind.

Application June 9, 1939, Serial No. 85,418

Term of patent 14 years

To all whom it may concern:

Be it known that I, Walter V. Smith, a citizen of the United States, residing at Hammond, in the county of Lake and State of Indiana, have invented a new, original, and ornamental Design for a Velocipede Deck Plate, of which the following is a specification, reference being had to the accompanying drawing, forming part thereof.

Fig. 1 is a top plan view of a velocipede deck plate showing my new design.

Fig. 2 is a rear elevational view thereof.

Fig. 3 is a front elevational view of the velocipede deck plate.

Fig. 4 is an end elevational view of the device.

I claim:

The ornamental design for a velocipede deck plate, substantially as shown.

WALTER V. SMITH.
